US0D1018677S

(12) **United States Design Patent** (10) **Patent No.:** **US D1,018,677 S**
(45) **Date of Patent:** **** Mar. 19, 2024**

(54) **GAMING MACHINE**

(71) Applicant: **SG GAMING, INC.**, Las Vegas, NV (US)

(72) Inventors: **Vernon Bernard**, Las Vegas, NV (US); **Robert J. Glenn, II**, Chicago, IL (US); **Scott T. Hilbert**, Sparks, NV (US); **Christian Kulujian**, Chicago, IL (US); **Paul M. Lesley**, Chicago, IL (US); **Gordon Myers**, Reno, NV (US); **Karl Wudtke**, Henderson, NV (US)

(73) Assignee: **LNW Gaming, Inc.**, Las Vegas, NV (US)

(**) Term: **15 Years**

(21) Appl. No.: **29/724,076**

(22) Filed: **Feb. 12, 2020**

Related U.S. Application Data

(63) Continuation of application No. 29/657,671, filed on Jul. 24, 2018, now Pat. No. Des. 886,905.

(57) **CLAIM**

The ornamental design for a gaming machine, as shown and described.

DESCRIPTION

FIG. 1 is a front right front perspective view of a gaming machine showing our new design;

FIG. 2 is a top view thereof;

FIG. 3 is a front view thereof;

FIG. 4 is a right side view thereof;

FIG. 5 is a rear view thereof; and,

FIG. 6 is a left side view thereof.

The broken lines depicting the remainder of the gaming machine illustrates environmental structure and form no part of the claimed design.

1 Claim, 6 Drawing Sheets
